UNITED STATES PATENT OFFICE.

LEOPOLD KRANZL, OF SEATTLE, WASHINGTON.

MILK-BOTTLE HANDLE.

Application filed July 21, 1922. Serial No. 576,489.

To all whom it may concern:

Be it known that LEOPOLD KRANZL, a citizen of the United States, residing at Seattle, in the county of King and State of

5 Washington, has invented certain new and useful Improvements in Milk-Bottle Handles, of which the following is a specification.

This invention relates to article carriers, 10 and particularly to bottle carriers.

The invention contemplates the provision of article engaging members with means for moving said members relatively to increase or decrease the spacing between the 15 members, so that the members may be placed over a bottle top having a beaded edge and the means operated to move the members for engaging the bottle below the bead, whereafter the bottle may be carried by 20 grasping a handle carried by said means.

The invention further provides article gripping elements having crossed ends, the body of the elements defining an opening adapted to fit over and grip the neck of a 25 bottle below an annular projection on the upper end and means receiving the ends adapted to pull the ends across one another to a greater or less extent so that a bottle will be gripped when the ends are crossed 30 to a greater extent.

In the drawings:—

Fig. 1 is a perspective view of the invention.

Fig. 2 is an end elevation with gripping 35 elements engaging a bottle.

A pair of article engaging elements 1 of semi-circular form have their end portions crossed as indicated at 2 and the outer ends formed with eyes 3 slidably mounted on the 40 diverging guide members 4. The end portion of one member overlies the other member on one end and lies under said member at the other end, so that in the upward or downward movement of the members on the 45 guides by an engaging member, the elements will have a balanced and even movement.

The guides 4 are joined at the lower ends by portions 5 formed with the guides and which serve as stops to limit the downward 50 movement of the article engaging elements. The guides meet at 6, one guide being secured to the other as indicated and above the point 6 one of the guide members is extended and curved into a lateral extending portion 7 having a handle 8 thereon, the portion 7 being formed in the central por-

tion of a piece of wire having the end portions bent to form two pairs of connected guide members as clearly illustrated in Fig. 1.

With the construction above described the gripping elements 1 will be moved to enlarge the opening between said elements when they are slid upwardly on the standards as indicated in dotted lines in Fig. 2 65 so that they may be passed over the upper beaded end of a bottle, and when permitted to drop by gravity the elements will be relatively moved by the guides for making said opening smaller for gripping the bottle below the bead thereon as shown in Fig. 2. The handle may now be grasped by the hand and the bottle carried in this position.

The members are released by pushing down on the handle which causes them to 75 be moved upon the guides and subsequently apart after which they may be disengaged from the bottle.

If desired coil springs 9 may be mounted 80 on the guides 4 engaging below eyes 3 and normally forcing the engaging elements upward on the standards for retaining them in article disengaging relation.

The weight of the bottle acting on the 85 engaging elements always tends to move the elements together for a better gripping action, so as to provide against a possible accidental disengagement of the bottle.

As illustrated, a wire has the center portion carrying the handle and the end portions bent laterally therefrom and formed to provide the guides and the stop portions on the bottom, enabling a strong and simple device to be cheaply and quickly manufactured.

What I claim is:—

1. In a carrier, article gripping elements, and diverging guides slidably receiving similar ends of said elements, said guides serving to relatively increase and decrease the spacing of the elements as the latter are moved longitudinally of the guides.

2. A carrier including article gripping elements, and downwardly diverging guides 100 slidably receiving the ends of said elements, said guides serving to relatively increase and decrease the spacing of the elements as the latter are moved upwardly or downwardly on said guides.

3. A carrier including article gripping 110 elements, downwardly diverging guides slidably receiving the ends of said elements,

said guides serving to relatively increase and decrease the spacing of the elements as the latter are moved upwardly or downwardly on said guides and stop members carried by the lower ends of the diverging guides for limiting the downward movement of said elements.

4. A carrier including article gripping elements, and downwardly diverging guides slidably receiving the ends of said elements, said guides serving to relatively increase and decrease the spacing of the elements as the latter are moved upwardly or downwardly on said guides, said elements being adapted for engagement with the neck of a bottle below a bead formed thereon, whereby the weight of the bottle on said elements will tend to move them downwardly on the guides to decrease the spacing.

5. A carrier including article gripping elements, downwardly diverging guides slidably receiving the ends of said elements, said guides serving to relatively increase and decrease the spacing of the elements as the latter are moved upwardly or downwardly on said guides, said elements being adapted for engagement with the neck of a bottle below a bead formed thereon, whereby the weight of the bottle on said elements will tend to move them downwardly on the guides to decrease the spacing and a handle carried by the upper ends of said guides.

6. A carrier including article gripping elements, downwardly diverging guides slidably receiving similar ends of said elements, said guides being joined together at the upper ends and serving to relatively increase and decrease the spacing of the elements in the upward or downward movement thereof on the guides, and a handle formed by a portion extending from the upper connected ends of the guides.

7. A carrier including article gripping elements, downwardly diverging guides slidably receiving similar ends of said elements, said guides being joined together at the upper ends and serving to relatively increase and decrease the spacing of the elements in the upward or downward movement thereof on the guides, a handle formed by a portion extending from the upper connected ends of the guides and stop members connecting the lower ends of the guides for limiting the downward movement of the elements thereon.

8. A carrier including article gripping elements, downwardly diverging guides slidably receiving the ends of said elements, said guides being joined together at the upper ends and serving to relatively increase and decrease the spacing of the elements in the upward and downward move-

ment on the guides, the elements being adapted to engage the upper portion of a bottle below a bead whereby the weight of the bottle will move the elements downwardly on the guides for reducing the spacing and providing a gripping of the bottle, and a handle formed by a portion extending from the connected upper ends of the guides by which the bottle may be carried.

9. A carrier including a pair of article gripping elements arranged to form a substantially cylindrical opening and having the ends thereof extending across the diametrical line of the opening, and means for varying the extension of the ends across said diametrical line for increasing and decreasing the size of the cylindrical opening.

10. A carrier including a pair of article engaging elements forming a substantially cylindrical opening between them and having the ends thereof extending across the diametrical line between the members, and diverging guides slidably receiving similar ends of said elements, said guides serving to vary the extension of the ends of the elements across said diametrical line in the longitudinal movement of the elements thereon for varying the size of the cylindrical opening.

11. A carrier including a pair of article engaging elements defining a substantially cylindrical opening and having the end portions extending across the diametrical line of the opening between the members, downwardly diverging guides slidably receiving similar ends of said elements, and serving to vary the extension of the end portions of the elements across said diametrical line for varying the diameter of the cylindrical opening in the upward or downward movement of said elements thereon, and a handle carried by said guides.

12. A carrier including a pair of article engaging elements defining a substantially cylindrical opening and having the end portions extending across the diametrical line between the elements, downwardly diverging guides slidably receiving similar ends of the elements and serving to vary the amount the ends extend across said diametrical line for increasing or decreasing the diameter of the cylindrical opening in the upward or downward movement respectively of the elements on the guides, said elements being adapted to receive a portion of a bottle having a bead on the upper end and engage below the bead whereby the weight of the bottle will move the elements downwardly on said guides for decreasing the cylindrical opening and gripping the bottle.

In testimony whereof I affix my signature.
LEOPOLD KRANZL.
